UNITED STATES PATENT OFFICE

169,511

COMBINATION GIRDLE AND BRASSIÈRE

Seraphina C. La Bue, Bronx, N. Y., and Henry P. Coogan, Fairfield, Conn., assignors to The Warner Brothers Company, Bridgeport, Conn., a corporation of Connecticut

Application January 12, 1953, Serial No. 23,100

Term of patent 14 years

(Cl. D20—4)

To all whom it may concern:

Be it known that we, Seraphina C. La Bue and Henry P. Coogan, citizens of the United States, residing respectively at the Bronx, New York, and Fairfield, Connecticut, have invented a new, original, and ornamental Design for Combination Girdle and Brassière, of which the following is a specification, reference being had to the accompanying drawings, forming a part hereof, in which:

Fig. 1 is a front elevational view of a combination girdle and brassière showing our new design.

Fig. 2 is a rear elevational view of said combination girdle and brassière.

We claim:

The ornamental design for a combination girdle and brassière, as shown.

SERAPHINA C. LA BUE.
HENRY P. COOGAN.
